United States Patent Office.

JOHN UMBACH, OF KANKAKEE, ILLINOIS.

Letters Patent No. 80,433, dated July 28, 1868.

IMPROVEMENT IN CONSTRUCTING BACK-PADS TO HARNESS.

The Schedule referred to in these Letters Patent and making part of the same.

TO ALL WHOM IT MAY CONCERN:

Be it known that I, JOHN UMBACH, of the city of Kankakee, in the county of Kankakee, in the State of Illinois, have invented a new and improved Method of Constructing Back-Pads to Harness; and I do hereby declare that the following is a full and exact description thereof, reference being had to the accompanying drawings, and to the figures of reference marked thereon.

The nature of my invention consists in the construction of back-pads to harness, in such a manner as to admit of the filling being introduced before the pad is stitched, to accomplish which the pocket or under side of the pad which contains the filling is first pressed by means of blocks to the required shape. This pocket so formed is then placed in a metal or wooden cup, shaped and formed similar to it. The filling is then evenly placed in, after which the top part of the pad is placed over, and with a strap or elastic band to hold them all firmly together, it is ready for placing in the clamps to be stitched.

To enable others skilled in the art to make and use my invention, reference is had to the annexed drawings, forming a part of this specification, in which—

Figure 1 is a plain view of the cup.

Figure 2 is a transverse section of the cup.

Figure 3 is a plain view of the one side to an ordinary back-pad, showing its upper surface as stitched to the pocket or cushion.

Figure 4 is a plain view of a pad, the same as shown in fig. 3, except a portion of the upper surface is broken away, showing the under part of the pad which forms the pocket or cushion to contain the filling.

Figure 5 is a cross-section of the cup, as shown in fig. 1, and also a cross-section of the pad, as shown in fig. 3, as contained in it during the process of stitching.

Figures 8 and 9 represent the convex and concave surfaces of the form-blocks used for pressing the pocket to its required shape, so as to form the under side of a back-pad.

Figure 6 is a cross-section, showing the convex surface of block 9, and

Figure 7 represents a cross-section, showing the concave surface in the block represented by fig. 8.

And a description of its construction and operation is as follows:

I construct my back-pad in the usual form of the tree-back pad, but in order to obviate the necessity of first basting the pocket or cushion part of the pad to the upper part of the same, and also to dispense with the necessity of putting the filling of the cushion in after one end and two sides of the pocket are stitched or closed up by the use of a rammer, and to make a durable and perfectly even cushion to back-band, I put the leather for the under part of the pad into the press or tree, as shown by blocks represented by figs. 8 and 9 in the accompanying drawings, fig. 8 representing the concave and fig. 9 the convex part of the press, as indicated by figs. 6 and 7, being transverse sections of figs. 8 and 9 respectively. The material being pressed between these convex and concave blocks sufficiently to retain this concavo-convex form, is then placed in the mould or cup, as shown by figs. 1 and 2, the convex surface of the pressed material is placed in the concave or cup of mould and the filling for cushion or pad is evenly distributed in the concavity of this pressed material as required, and the upper part of the back-pad is then put on the opening of the cup containing the pressed outer material for cushion, and the filling of cushion as represented by drawings marked 3 and 4, and there secured by leather or rubber bands ready for placing in the clamps to be stitched; the moulding or cup over the cushion of the under side of the pad preventing any disturbance of the filling in the process of stitching, as represented in cross-section marked 5 on said drawings.

What I claim as my invention, and desire to secure by Letters Patent, is—

The use and application of the moulding or cup, in the filling and stitching the cushion or under part of the back-pad to harness.

JOHN UMBACH.
